GAS HEATERS OF THE OVERHEAD TYPE
Edwin J. Cowan, 475 Gatewood Lane, Sierra Madre, Calif.
Filed Feb. 3, 1958, Ser. No. 712,845
5 Claims. (Cl. 126—91)

This invention relates to heating devices and more particularly to gas heating devices and still more particularly to gas heating devices of the overhead type; and has for its object the provision of an improved gas heater of the overhead type.

Another object is to provide a gas heater of the overhead type in which a horizontally disposed primary heat radiating floor or body is provided in the bottom thereof for the downward radiation of heat therefrom to areas and objects in range of the bottom surface of said floor or bottom, and wherein means is provided to heat the upper surface of said floor directly by means of a gas burner disposed above the primary heat radiating floor or body.

A further object is to provide means effective to promote a high rate of heat exchange between a gas burner emanating heat energy at one horizontal level and a primary heat radiating floor or body disposed in a horizontal plane adjacent to but below the horizontal level of said gas burner.

Still another object of the invention is to provide a low pressure gas heater of the overhead type having an enclosed flame and a means to vent the gases of combustion therefrom which is characterized by having a bottom area thereof comprised of material adapted to function efficiently as a primary heat radiating body, said body being disposed substantially in a horizontal plane and wherein a low pressure gas burner means is provided for heating said primary heat radiating body directly by heat transfer from said burner, said gas burner means being disposed at a horizontal level adjacent to but above the horizontal level of said primary heat radiating body.

A further object is to provide a low pressure gas heater of the overhead type having a heat radiating area disposed in the floor or bottom thereof in a horizontal plane relative to the vertical plane of suspension of the heater and a low pressure gas burner means within the heater disposed at a horizontal level above the said heat radiating area but adjacent thereto which is adapted to heat said area by the direct transfer of heat energy thereto.

Other objects will be apparent as the invention is more fully hereinafter disclosed.

Before further disclosure of the invention, reference should be made to the accompanying drawings wherein are disclosed several specific embodiments or species of the invention.

In the drawings:

FIGURE 1 is a top view of one specific embodiment of an overhead gas heater device conforming to the present invention;

FIGURE 2 is a sectional view of the same taken along plane 2—2 of FIGURE 1;

FIGURE 3 is a second sectional view of the same taken along plane 3—3 of FIGURE 2.

Referring to FIGURES 1 to 3 inclusive, the overhead gas heater device shown therein is one adapted to be suspended from a ceiling by means of rods 10—10' anchored at the upper end to the ceiling and secured at the other end to the top or cover of the heater, generally indicated by letter H, in any convenient or desired manner. The specific means for dependently securing the heater H to the rods 10—10' or to the ceiling, per se, forms no part of the present invention.

The heater H of the present invention consists of two

2

annular concaved or bowl-like parts 1—2, each provided with a rim-flange 3—3' extending in the same direction outwardly from the rim-periphery which flanges 3—3' are adapted to be joined together by means of a plurality of bolts and nuts 4 with a sealing ring 5 secured therebetween to form the body part generally indicated as heater H. The lower part 2 constitutes a pan containing the burner head 14, and the upper part 1 constitutes a top or cover. As best seen in FIG. 2, the bottom of the pan 2 is substantially flat with the periphery curving upward to form sides.

The upper part or cover 1 of the heater H is provided with a vent or flue 6 opening to the interior of the body part and providing for the escape of gases or products of combustion from the interior of the heater and for the delivery of same to a chimney conducting the gases out of the room or enclosed area within which the heater H is located.

Flue 6 is provided with a downdraft diverter consisting of an opening or aperture 31 formed in the side of the flue 6 and a baffle plate 32 spanning the interior of the flue 6 and located opposite aperture 31. A segment is cut from the plate 32 opposite the aperture 31, as shown at 33.

The upper cover part 1 of the heater H also is provided with a coaxial annular opening centered at the center transverse axis of the cover part 1 within which is seated and secured a depending tubular partition or wall 7, the lower edge of which lies in approximately the same plane as the engaging flanged rims of the parts 1 and 2.

Extending coaxially outward and overlying the opening defined by the tubular partition 7 is a plate or shield 8 mounted on a coaxial burner 9. The shield 8 protects the valve assembly thereabove from excessive heat.

Means, including a pressure-reducing valve 11 and a shut-off valve 12, each of common and well known design, is provided to feed gas from gas main 13 admixed with the proper amount of primary air for combustion to the burner head 14. The specific combination forming this means is, per se, no part of the present invention except as it is necessary and essential to the operation of the heater H.

Burner 9 is designed such that with respect to the vertical height of the heater H, the burner length is such as will locate the burner head 14 thereof adjacent to the bottom of the bowl or pan part 2 of the heater H. The outside periphery of the burner head 14 is provided with circumferentially spaced gas ports or openings 15, whose axes lie in a plane substantially normal to the axis of burner 9 and in a horizontal plane substantially parallel to the horizontal plane of the bottom wall of the pan part 2, thereby to direct the gas flame 16 emitted therefrom circumferentially over a substantial area of the said bottom and in relatively close proximity thereto.

With this arrangement of the burner and burner parts, it will be recognized that the burning gases 16 circumferentially emitting from the plurality of ports 15 in the burner head 14 form an annulus of radially outward flame cones disposed in a substantially horizontal plane hugging or closely superjacent the horizontal inner or upper surface of the pan or bowl 2 and would normally tend to travel therealong following the arcuate inner surface thereof upwardly into the upper cover part 1 of the heater and thence out of the combustion chamber enclosed by parts 1 and 2 into the flue 6, the tubular portion 7 in the cover part 1 preventing these gases of combustion from passing out through the inlet opening defined by the partition 7.

Where the air-gas mixture supplied to the burner for combustion in the combustion chamber defined by the

parts 1 and 2 consists of a low-pressure gas-air mixture, additional air is required for complete combustion. This additional air enters the combustion chamber through the opening defined by tubular partition 7, and mixes with the flame cones 16 at the base thereof, the direction of flow of this air being indicated by arrows. Air mixing continues radially outward from the base of the flame cones. It will be noted that the flow of this air is through the space gap defined by the lower edge of the tubular partition 7 and the upper surface of the burner head 14. This space gap may be varied widely without essential departure from the invention but it general is utilized to control or regulate the velocity of the incoming air required for complete combustion. By increasing or decreasing this space gap, the velocity of the air is either decreased or increased and under any given set of conditions of heater size (diameter), diameter of burner head relative thereto and pressure of the air-gas mixture being fed to the burner head, an optimum space gap providing the proper velocity of air flow into the chamber for the functional result in view may be selected or determined without undue experimentation. The functional result desired for this air flow in the present invention is to maintain the flame 16 depressed in a substantially horizontal plane over substantially the greater area of the flame by counteracting its normal tendency to rise upwardly as the pressure of the gas-air mixture falls after passing through the port openings 15.

Air which is pre-mixed with the combustible gas before the gas flows into the burner head 14 is called "primary" air. Air which mixes with the gas in the flame 16 after the gas has emerged from the burner ports 15, and which enters chemically into the combustion of the gas, is called "secondary" air. In this specification the term "excess" air refers to all of the outside air which is drawn into the combustion chamber through the tubular inlet 7. A portion of this excess air enters into the combustion process and becomes secondary air. That portion which does not enter into the combustion process but merely mixes with the combustion gases and then flows out through the exhaust flue 6 is, in this specification, called "dilution" air.

The attainment of this functional result is not difficult nor critical where, as in this specific embodiment, the bottom wall of the heater H is substantially imperforate. In this situation, substantially all of the excess air, i.e., secondary and dilution air, must enter the combustion zone through this space gap and the velocity of the air flow through the gap will function, as desired, to maintain the flame depressed closely superjacent the bottom wall over the greater portion of the surface thereof to a greater or lesser degree depending on the velocity of the air and to carry the gases of combustion toward the curved sides and upwardly therealong into the upper cover chamber 1 for discharge into the flue 6.

The important result obtained by the burner means and depression of the flame is that the bottom part or pan is heated directly by heat exchange with the horizontally projected burning gases of combustion from the burner head 14 over its greater area and that this result is attained relatively rapidly and efficiently.

By comprising this bottom wall of the pan 2, at least, of material adapted to absorb heat rapidly and the bottom surface of the wall, at least, of material adapted to radiate this absorbed heat effectively and directly to objects and persons, directly under the surface and in view of same, a more efficient and effective gas-fired overhead radiant heater device results.

It has been found that for most purposes and most installations, part 2 of the heater H may be comprised of a metallic composition such as an oxidation-resistant ferrous metal alloy, preferably one which is sufficiently malleable in sheet form to be fabricated as by stamping methods into the flanged bowl or pan shape shown. A plurality of such oxidation-resistant ferrous metal alloys

are available in the art and each has differing but favorable properties for the purpose of this invention. Alternatively, a number of copper alloys are available in the art for utilization in the forming of part 2 of the heater H. Many other types of alloys are also adapted for utility in this invention and the specific composition of the metallic pan part 2 is not contemplated as being within the scope of this invention.

Cover part 1 of the heater H may be comprised of the same metallic composition as comprising pan part 2 or it may alternately be comprised of material less absorptive of heat radiation or it may be surfaced exteriorly with thermal insulating material, such as asbestos, or glass wool, so as to adapt the device to be dependingly sustained in closer spaced relation to a ceiling without fire hazard.

It is believed apparent from the above disclosure and accompanying drawings illustrating the same that the present invention is adapted to wide utility in the art and that many modifications, changes and alterations may be made therein without essential departure therefrom and all such changes, modifications and adaptations of the invention as herein disclosed and illustrated in the drawings are contemplated as may fall within the scope of the appended claims.

What is claimed is:

1. Heater comprising a bowl made of non-combustible material and having a generally flat bottom adapted to radiate heat, a burner head disposed adjacent said bottom and having burner ports directed in a substantially horizontal plane, thereby to emit burnable gas to form a flame superjacent a substantial area of said bottom, said area being substantially imperforate, thereby to preclude the introduction of excess air into the burner flame from beneath the flame, a cover substantially covering said bowl, and conduit means for admitting excess air into said bowl and terminating immediately above the level of said burner head, whereby substantially all of the excess air which mixes with the flame does so from above the flame said cover being spaced appreciably above the level of the termination of said excess air conduit means, there being a substantially unobstructed space above the level of said ports to a level substantially above the level of the termination of said excess air conduit means, whereby a layer of excess air is formed above the flame over substantially its entire extent to maintain the flame depressed toward said bottom.

2. Heater comprising a pan made of non-combustible material and having a generally flat bottom adapted to radiate heat, a burner head disposed adjacent said bottom and having burner ports directed in a substantially horizontal plane paralleling said bottom, thereby to emit gas to form a flame closely superjacent said bottom, said bottom being substantially imperforate, thereby to preclude the introduction of excess air into the flame from beneath the flame, an excess air inlet conduit directed downwardly and having its discharge edge located above the burner ports and rearwardly thereof with respect to flow of gas from said ports, a cover for said heater substantially covering said pan and located appreciably above the discharge edge of said excess air conduit, whereby a layer of excess air is formed superadjacent the flame over substantially its entire area, thereby to maintain the flame depressed toward said bottom, and means at the top of said heater for discharging combustion products therefrom.

3. Heater comprising a bowl made of non-combustible material and having a substantially flat bottom adapted to radiate heat, a generally circular burner having burner ports directed substantially parallel to said bottom, thereby to emit a burnable gas to form a flame superjacent a substantial area of said bottom, said area being substantially imperforate, thereby to preclude the introduction of appreciable excess air into the flame from beneath the flame, a cover substantially covering said bowl, an

excess air inlet conduit extending downwardly into said bowl and terminating in a discharge edge spaced appreciably below said cover and immediately above said burner ports, thereby to introduce excess air into the heater above the flame for maintaining the flame depressed toward said bottom, and means at the top of said bowl for discharging combustion products therefrom.

4. Heater adapted for overhead installation comprising a bowl made of non-combustible material and having a substantially flat bottom adapted to radiate heat, a generally circular burner head disposed adjacent said bottom and having burner ports directed outward to form a flame substantially parallel to said bottom, a cover substantially covering said bowl and spaced appreciably above said burner ports, an excess air inlet conduit passing through said cover and extending downwardly to terminate in a discharge edge disposed above said burner ports and spaced appreciably below the inner surface of said cover, whereby a layer of excess air is formed above the flame and substantially covering the same, thereby to depress the flame toward said bottom, and means at the top of said bowl for discharging combustion products therefrom.

5. Heater adapted for overhead installation comprising a bowl made of non-combustible material and having a substantially flat bottom adapted to radiate heat, a generally circular burner head disposed adjacent said bottom and having burner ports directed outward to form a flame substantially parallel to said bottom and immediately superjacent thereto over a substantial area thereof, 80

said area being substantially imperforate, thereby to preclude the introduction of excess air into the flame from beneath the flame, a cover substantially covering said bowl and spaced appreciably above said burner ports, an excess air inlet conduit passing through said cover and extending downwardly to terminate in a discharge edge disposed above said burner ports and spaced appreciably below the inner surface of said cover, whereby a layer of excess air is formed above the flame and substantially covering the same, thereby to depress the flame toward said bottom, and means at the top of said bowl for discharging combustion products therefrom.
